MULTIPLE KEYBOARD UNIT

Percy Dean Olson, Owatonna, Minn., assignor to
Musitronic, Inc., Owatonna, Minn.

Original design application Dec. 14, 1970, Ser. No. 26,453.
Divided and this application Nov. 12, 1971, Ser. No.
198,486

Term of patent 14 years

Int. Cl. D17—01

U.S. Cl. D56—9

FIG. 1 is a top plan view of a multiple keyboard unit showing my new design;

FIG. 2 is a side elevational view of FIG. 1, the opposite side being substantially a mirror image thereof;

FIG. 3 is an end elevational view, looking at the right end in FIG. 1; and

FIG. 4 is an end elevational view looking at the left end in FIG. 1.

This is a division of application Ser. No. 26,453, filed Dec. 14, 1970.

I claim:

The ornamental design for a multiple keyboard unit, substantially as shown and described.
